CLAIM

The ornamental design for an air compressor work table, as shown.

DESCRIPTION

FIG. 1 is a top, left side perspective view of an air compressor work table showing our new design. The broken lines are for illustrative purposes only and form no part of the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
